UNITED STATES PATENT OFFICE.

EDWARD P. CRESSLER, OF NEWTON, KANSAS, ASSIGNOR TO COOK LABORATORIES, INC., OF CHICAGO, ILLINOIS, A CORPORATION OF DELAWARE.

HYPODERMIC SYRINGE.

Original application filed January 30, 1924, Serial No. 689,518. Divided and this application filed March 22, 1928. Serial No. 263,670.

This application is a division of my application filed January 30, 1924, Serial No. 689,518, relating to hypodermic syringes of the cartridge type.

5 In said prior application, I disclose several examples of a syringe organization embodying a cartridge or sealed container of hypodermic fluid, contractible in interior volume for expelling the contents, and the 10 discharge end of which is controlled by internal fluid pressure for establishing communication with a hypodermic injecting needle when the pressure is applied and for shutting off communication with the needle 15 when the pressure is released, so as to avoid the drawing of blood or foreign matter from the patient's tissue into the injecting needle by any suction effect in the cartridge accompanying rebound or retractive movement of 20 the syringe plunger. More specifically, the cartridge is sealed at its discharge end by a flexible closure so constructed as to provide a central passage therethrough which is 25 opened by outward flexing of the closure under pressure imposed on the liquid in the cartridge and closed by reflexing of the sealing closure when the pressure on the liquid is released. The injecting needle of the 30 syringe organization has or is connected with an inner funnel extension the inner larger 35 end of which bears against the outer face of the cartridge sealing closure, thus providing an annular seat or abutment cooperating with the flexible closure to control its flexing movement and to assure discharge of the liquid ejected from the cartridge to and through the needle.

The improvements described and claimed in said prior application include a cartridge 40 and cartridge syringe organization of the general character above noted, and in general the novel features, constructions and combinations embodied in or common to the several organizations illustrated in said prior 45 application.

One syringe organization and cartridge therefor illustrated in said prior application, embodying the invention or improvements therein claimed, and upon which this 50 divisional application is based for specifically claiming further specific subject-mat-

ter, are respectively shown in the drawings hereunto annexed.

In said drawings:

Fig. 1 is a longitudinal section of said 55 syringe or injection-administering organization;

Fig. 2 is a longitudinal section of the cartridge;

Figs. 3 and 4 are enlarged sections of the 60 discharge end of the cartridge, the section of Fig. 4 being taken at right angles to the section of Fig. 3.

As represented in the drawings, a plug 2 of resilient material such as soft rubber or 65 the like, fitted as a stopper in the fore end of the glass cartridge tube 1, and formed with a flange overlying the edge of the glass tube, seals the discharge end of the illustrative cartridge. Said plug has at its center 70 a conical cavity 2^a extending part way through the plug from its inner side, and a slit or incision 2^b cut in the outer side of the plug and meeting the cavity 2^a. The form and relation of said cavity and slit are such 75 as to provide in effect a pressure-controlled valve opening outwardly under pressure imposed on the liquid in the cartridge, to permit discharge of the liquid, and automatically closing when the pressure is released. 80 That is to say, normally or in the absence of pressure on the contained fluid the walls of the slit 2^b are pressed tightly together, but when pressure is imposed on the liquid by forcing in the rear piston plug 3 the plug 85 or its central portion will flex, so that the walls of the conical cavity 2^a will tend to become parallel to each other and the walls of the slit 2^b will separate from each other, thereby opening a passage in the sealing 90 plug, and when the pressure is released the reflexing of the plug will press the walls of the slit together and close said passage.

In the syringe organization, the hypodermic needle 4 has an inner funnel extension 5, preferably integral with the needle. The needle funnel 5 is held with its inner edge against the outer face of the sealing plug 2, surrounding the central passage thereof, thereby presenting an annular ledge 100 or seat cooperating with the sealing plug to control its flexing and to assure the dis-

charge of the liquid ejected from the cartridge into and through the needle via the funnel.

The cartridge is shown fitted in a tubular 5 syringe body or cartridge holder 6, having longitudinal sight openings 7. A head 8 screwed on the fore end of the syringe body provides an abutment for the sealing plug 2. This head 8 has an exteriorly threaded 10 tubular nipple 9 of sufficient internal diameter to accommodate the needle funnel 5. The needle holder 10 comprises a screw cap screwed upon the nipple 9, said cap having a tapered axial bore to fit the needle funnel 15 5, so that the needle is held substantially rigidly with the inner end of the funnel bearing against the outer face of the sealing plug 2.

The cartridge plug 3, functioning as a 20 piston to be forced inwardly to cause the opening of the passage in the discharge end of the cartridge and ejection of the fluid, is represented as a composite plug comprising a relatively thicker hard rubber section 25 3^a and thin soft rubber section 3^b, the thicker section being fitted in the glass cartridge tube less snugly than the soft rubber section. When this composite plug is forced inward, the thicker harder section 2^a will 30 slide freely, and the soft section will trail behind it without marked binding tendency; but if the movement is reversed the softer rubber section traveling in advance of the harder rubber section will be expanded and 35 spread so that its frictional contact with the interior of the glass tube will retard the movement and act with a braking effect. This is advantageous in resisting tendency of rebound at the end of the fluid-ejecting 40 stroke of the syringe plunger.

The syringe plunger is shown as a rod 11 having a threaded end for screw engagement with the composite plug, the sections of which are formed with holes for such 45 engagement, though it will be understood that the plunger may be engaged with the plug otherwise. For operating the syringe, the operator grasps the finger pieces 12 attached to the rear end of the syringe body 50 and bears with the palm of his hands on the handle 13 of the plunger rod to drive in the piston plug. The plunger rod is carried by the cap 14 detachably secured on the rear end of the syringe body, as for instance by 55 means of pins 15 engaging bayonet slots in the rear end of the syringe body. A stop 16 on the plunger rod limits the outward movement of the rod. The proportions of the cartridge and instrument parts are desirably such that when the breech cap 14 is applied it will bear against the butt end of the cartridge tube and hold the cartridge substantially against longitudinal movement with the fore sealing plug 2 against 60 the abutment provided by the head 8. The

cartridge being so held and the flange of the plug 2 overlying the fore end of the glass tube, the needle may be held with the inner end of its funnel head seated against the sealing plug with desired pressure. In 75 the fluid-ejecting operation, the end thrust imposed upon the glass cartridge tube is cushioned by the flange of the sealing plug, which is clamped between the head 8 and the glass tube, serving as a gasket and cushioning means and to protect the end of the tube.

It will be understood that in addition to the subject-matter herein claimed the illustrative cartridge and injection-administering organization embody broader subject-matter claimed in my said prior application Ser. No. 689,518.

I claim herein:

1. A hypodermic syringe embodying a 85 cartridge and needle in operative relation, said cartridge comprising a tube having liquid-confining plugs, one to be forced inward as a piston and the other constructed to provide a normally closed sealing stop- 90 per responsive to pressure imposed on the liquid to establish a discharge passage through the plug, said needle having a funnel held with its mouth against said plug and surrounding the passage therethrough, 95 with associated means holding the cartridge and needle in assembly and means for forcing in said piston plug.

2. A hypodermic syringe embodying a 100 cartridge and needle in operative relation, said cartridge comprising a tube having liquid-confining plugs, one to be forced inward as a piston and the other sealing the discharge end of the tube and constructed to provide a pressure-controlled passage 105 opened by pressure imposed on the liquid by the forcing in of said piston plug and closing when said pressure is released, with associated means holding the cartridge and needle in assembly and means for forcing in 110 said piston plug.

3. A hypodermic syringe embodying a 115 cartridge and needle in operative relation, said cartridge comprising a liquid-containing tube having a rear piston plug and a fore sealing plug of elastic material having a flange overlying the end of said tube, said sealing plug constructed to provide a pressure-controlled passage opened by pressure imposed on the liquid by the forcing in of 120 said piston plug and closing when said pressure is released, with a cartridge holder providing an abutment for said flanged sealing plug and having the needle removably connected therewith, and means for driving in 125 the piston plug.

4. In a syringe organization of the character described, the combination with a liquid-containing cartridge contractible in interior volume and having a sealing plug 130

- of elastic material constructed to provide a pressure-controlled passage openable by pressure imposed on the liquid, of a hypodermic injecting needle having an integral 5 funnel held with its mouth against said plug around said opening, and associated means holding said cartridge and needle in operative relation.
5. A cartridge-holding body having a head 10 to provide an abutment for the fore end of the cartridge inserted therein, said head having an externally threaded nipple of substantially large internal diameter to accommodate a needle funnel, and a needle-holding 15 screw cap engaging said nipple having a tapered bore to fit the funnel and thereby hold the same with its mouth against the cartridge.
6. A syringe cartridge comprising a 20 liquid-containing tube having liquid-confining plugs, one to be forced inward as a piston and the other having a pressure-controlled discharge passage adapted to open under pressure imposed on the liquid and to 25 close when the pressure is released.
7. A syringe cartridge comprising a 20 liquid-containing tube having liquid-confining plugs, one to be forced inward as a piston and the other comprising an elastic stop- 30 per having a flange overlying the end of the tube and constructed to provide a pressure controlled passage operable by pressure
- imposed on the liquid by the forcing in of said piston plug and adapted to close when the pressure is released. 35
8. A medicament container having a flexible rubber plug sealing one end thereof; said plug provided with a substantially axial cavity extending part way through the plug from the inner wall, and provided with an 40 axial slit extending from the cavity to the outer wall of the plug; the plug being so constructed and arranged that the cavity is normally open, while the slit is normally closed, but under the pressure created during an injection, the body of the plug flexes and the slit is opened to permit discharge of the medicament through the passageway provided by the cavity and slit together. 45
9. A medicament container having a flexible rubber plug closing one end thereof; said plug provided with a substantially axial conical cavity extending part way through the plug from the inner wall, and also provided with a straight-walled slit extending 50 from the bottom or small end of the cavity to the outer wall of the plug; the plug being so constructed and arranged that the slit is normally closed to seal the container, but is opened by flexure of the plug from pressure within the container. 55

In testimony whereof, I have signed my name to this specification.

EDWARD P. CRESSLER.
